UNITED STATES PATENT OFFICE.

AUSTIN CHAMBERS, OF No. 258 MARYLEBONE ROAD, GREAT BRITAIN.

IMPROVEMENT IN PNEUMATIC SIGNALING APPARATUS.

Specification forming part of Letters Patent No. 175,421, dated March 23, 1876; application filed November 18, 1875.

To all whom it may concern:

Be it known that I, AUSTIN CHAMBERS, of No. 258 Marylebone Road, in the county of Middlesex, Kingdom of Great Britain and Ireland, signal engineer, have invented Improvements in Pneumatic Signaling Apparatus for Railways, of which the following is a specification:

This invention has for its object improvements in signaling apparatus for railways, and has reference, mainly, to improvements upon and further developments of the invention forming the subject of Letters Patent granted to me the 11th May, 1875, No. 163,152, in which the semaphore-arms or signaling objects or bodies are operated pneumatically, in such wise that when the pressure of the external atmosphere prevails in the pipes, tubes, or passages establishing communication between the signaling station or place and the device which moves the semaphore-arm or other signaling object, the latter is in the position indicative of "danger."

My invention relates, principally, to the combination, in a railway-signaling apparatus, of a pipe, tube, or passage charged with air or other elastic fluid, means or apparatus for changing the pressure thereof, a collapsible vessel or chamber, a gas or other burner connected to said collapsible vessel or chamber, and fixed glasses or lenses, the whole being so arranged as, by changing the pressure of the air or elastic fluid in the apparatus, to effect the necessary movements or changes of position of a light relatively to said fixed glasses or lenses.

Figure 1 of the drawing shows in elevation an ordinary signal-post, provided with a semaphore-arm and with fixed colored lenses, a movable burner, and apparatus for actuating the same pneumatically according to my invention. Fig. 2 is a sectional plan view, showing the top of the lantern and collapsible vessel. Fig. 3 is a side elevation of the compressor or at right angles to Fig. 1. Fig. 4 is a plan of the compressor.

a is the signal-post; *b*, the semaphore-arm; *c*, the lantern, divided into two chambers, *c*¹ *c*²—one above the other—by an internal division, *c*³, which is formed with a hole, through which the burner *d* passes, guided by the

frame *e*. The upper chamber is provided with a lens, *c*⁴, for indicating "safety," or "pass on," and the lower chamber with a "danger-lens," *c*⁵. The burner *d* is supplied with gas through the flexible tube *f*, and is connected to the rod *g*, which also operates the semaphore-arm, and is itself actuated by the collapsible vessel *h*, to the upper end of which the rod is connected. The part *h*' of the collapsible vessel is made of india-rubber or other flexible material, and the other parts may be made of metal, so that when the pressure in the pipe (hereinafter mentioned) does not exceed the normal pressure of the external atmosphere, the vessel *h* will be collapsed. From the fixed lower end of the vessel *h* a pipe, *i*, communicates with the interior of a collapsible vessel, *k*. (Shown also in Figs. 3 and 4.) The lower end of this collapsible vessel *k* is a fixture. Its upper end carries a guide-rod, *k*³, working in guides *k*⁴, as also a tube, *k*⁵, for guiding the rod or stem *l*⁴ of a weight, *l*⁵, connected by a chain, *l*⁶, or equivalent means, to the shorter arm *l*¹ of the lever *l*. The upper end of the collapsible vessel *k* also has connected to it a couple of chains, *j*, passing over pulleys *j*¹, carried by the fixed frame *k*¹, the chains being provided with weights *j*².

In Fig. 1 the lever and the parts shown in section in the right-hand portion of the compressing apparatus represent the positions of the parts when the air or gas in the pipe *i* has been compressed, and has expanded or opened out the vessel *h*, raised the rod *g* and burner *d*, and lowered the semaphore-arm *b*.

When the pressure in the pipe *i* does not exceed the pressure of the external atmosphere, the weight of the rod *g*, with its attachments, preponderates over that of the semaphore-arm *b*, thereby retaining the latter in the horizontal position, indicating "danger" at all times, until the pressure in the pipe *i* is increased, so as to move the parts into the positions shown in Fig. 1.

On drawing the lever *l* over in the direction of the arrow into the position indicated by the dotted line, Fig. 1, the weight *l*⁵ will be instantaneously raised, thus releasing the upper end of the collapsible vessel *k*, which will be gradually drawn up by the weights *j*² and chains *j*, without its being necessary for the opera-

tor to keep hold of the lever l , as this lever will be retained in the position to which it has been moved by an ordinary spring-catch. To again compress the vessel k , it is simply necessary for the operator to move the lever l back into the position shown in Fig. 1, and to leave it locked. The weight l^5 will gradually close the vessel k . I provide valves or cocks m at intervals in the pipe i , leading to distance-signals, whereby the guard of a train or other official may, when necessary, (as, for example, when a train has passed within a distance-signal, and another train is heard in front, but is not visible,) reduce the pressure in the pipe i to that of the external atmosphere, and thereby cause the signal to assume the horizontal position, indicative of "danger." i^1 is a pipe leading to the office of the station-master, platform-foreman, or other official, wherein is placed an ordinary U-shaped glass water-gage or indicator, i^2 , the liquid in which, being actuated by the changes of pressure in the pipe i , will afford a simple and efficient check upon the signal-man in the box containing the lever l . n is an adjustable valve, which may be so adjusted by the station-master or other official as to alter the pressure in the pipe i , either to bring the semaphore-arm or signaling body at once to the "danger" position, or to cause it to assume that position within any given time by a gradual leakage of air or elastic fluid from the pipe through the valve.

Fig. 5 is a modification adapted for signaling entirely by means of a light. In this case the lamp is divided into three compartments, $c^1 c^2 c^9$, by two internal divisions, $c^3 c^{10}$, the collapsible vessel h being arranged within the lower compartment c^9 , and carrying the burner d , which is fed by a flexible tube, f , or otherwise. c^4 is the safety-lens, and c^5 is the danger-lens. The operation of this arrangement will be evident.

Figs. 6, 7, and 8 show a modification in which the light is carried by a swinging arm or bracket, p . The lamp is divided into two compartments, $c^1 c^2$, in the present case, by a vertical division, c^3 , slotted at c^{11} , and the burner carries two small plates or shutters, $c^{12} c^{13}$, for closing the slot c^{11} , to prevent the light passing from one compartment of the lamp to the other. The collapsible vessel h has connected to it one end of a cord or chain, p^1 , which passes over a couple of pulleys, p^2 p^3 , and at its other end carries a weight, p^4 . This cord or chain is attached to the swinging bracket, so that when the collapsible vessel h is expanded, as shown, the weight p^4 moves the bracket into position for showing the light through the safety-lens c^4 , and when

the collapsible vessel h is collapsed, its end of the cord or chain p^1 is drawn down, thus moving the bracket and burner into the position for showing the light through the danger-lens c^5 .

The drawing shows a burner designed to carry a candle; but it will be evident that brackets carrying oil or other burners may be substituted for the candle arrangement shown, or the bracket may carry a gas-burner fed by a flexible tube; or, in lieu of the bracket shown, an ordinary swinging gas-bracket may be substituted therefor, so as to be operated in the manner shown in and described with reference to Figs. 6, 7, and 8.

It will be evident that the apparatus above described may be modified so as to move down the semaphore-arms and burners for indicating "safety" by rarefying air or reducing the pressure of the elastic fluid in the pipe i on moving over the actuating-lever.

Having described my said invention and the manner of carrying it into practical effect, I claim—

1. The combination of the vessel h h' , pipe i , charged with elastic fluid, compressor k , operated by weights j^2 l^5 , and the rod g , connected to the semaphore-arm b , and burner c^1 , fed with gas by the flexible tube f , and guided by the frame e , so as to operate in conjunction with the "safety" and "danger" lenses c^4 c^5 of the lamp c , carried by the post a , all in the manner shown in and described with reference to Figs. 1, 2, 3, and 4, for the purpose specified.

2. As part of a pneumatic signaling apparatus for railways, the pressure-changing apparatus, consisting of the lever l l' , chain l^6 , weight l^5 , stem l^4 , tube l^5 , rod k^3 , guide k^4 , collapsible vessel k , chains j , pulleys j^1 , and weights j^2 , the whole so arranged that the lever may be instantaneously moved over, and that the expansion or collapse of the chamber to alter the signal will be completed automatically, as above described, for the purpose specified.

3. The combination, with a lantern, c , slotted division c^3 , lenses c^4 c^5 , pipe i , charged with elastic fluid, and apparatus for changing its pressure, of a collapsible vessel, h , burner d , weight p^4 , cord or chain p^1 , pulleys p^2 p^3 , and bracket p , all substantially in the manner shown in Figs. 6, 7, and 8, for the purpose specified.

AUSTIN CHAMBERS.
